UNITED STATES PATENT OFFICE.

ABNER A. BEVIN, OF EAST HAMPTON, CONNECTICUT.

DESIGN FOR A GONG FOR BELLS.

SPECIFICATION forming part of Design No. 28,076, dated December 21, 1897.

Application filed October 4, 1897. Serial No. 654,085. Term of patent 7 years.

To all whom it may concern:

Be it known that I, ABNER A. BEVIN, a citizen of the United States, residing at East Hampton, in the county of Middlesex and State of Connecticut, have invented and produced a new and original Design for a Gong for Bells, of which the following is a specification, reference being had to the accompanying drawings, forming a part thereof.

10 Figure 1 is a view in side elevation of a gong, showing my new design. Fig. 2 is a top or plan view.

As shown in the drawings, the leading or material feature of my design consists of a 15 lower portion having the form of the frustum of a cone, and the upper portion of the gong

having the form of a cone, the sides of which are inclined to a less degree than are the sides of the lower portion, thus forming a distinct angle between the lower and upper parts of 20 the gong when viewed in side elevation, as shown in Fig. 1.

Having described my invention, what I claim as new, and desire to secure by Letters Patent, is—

25 The design for a gong for a bell substantially as herein shown and described.

ABNER A. BEVIN.
